CIGAR FEED

Joseph A. Neumair, Hollis, N. Y., assignor to
 International Cigar Machinery Company, a
 corporation of New Jersey

Application September 29, 1934, Serial No. 746,234

10 Claims. (Cl. 198—210)

This invention relates to an improved cigar feed for combined wrapping and banding machines, and more particularly to a cigar feed designed to receive the cigars from a magazine placed at right angles or any other desired angle to the length of the machine and swing them a quarter-turn or other required fraction of one revolution, and deliver them to the conveyor of the machine. Accordingly, the main object of the invention is to transport the cigars one by one from the rows delivered from the magazine, and swing them through an arc of 90 degrees or other desired angle, and deliver them to the conveyor which advances the cigars to the banding and wrapping mechanisms of the machine. With this and other objects not specifically mentioned in view the invention consists in certain constructions and combinations hereinafter fully described and then specifically set forth in the claims hereunto appended.

In the accompanying drawings which form a part of this specification and in which like characters of reference indicate the same or like parts:

Fig. 1 is a partial side view of a wrapping and banding machine provided with the improved cigar feed;

Fig. 2 is a partial end view of the same;

Fig. 3 is a detail view of the cigar feed showing the turn-table which swings the cigars through an arc of 90 degrees; and

Fig. 4 is a plan view of the turn-table showing the cigar receiving and discharging stations thereof.

In carrying the invention into effect there is provided a pair of spaced endless belts adapted to feed a row of cigars sidewise, a turn-table revoluble about a vertical axis and provided with a plurality of sets of horizontal jaws at equal intervals thereon, each set being adapted to grip a cigar inserted therebetween, means for transporting the leading cigar from said row and inserting it into the set of jaws then at the receiving station of the turn-table, mechanism for periodically turning the turn-table about its vertical axis through a fraction of one revolution to carry the gripped cigar to the discharging station of the turn-table, a turret revoluble about a horizontal axis and provided with sets of radial grippers adapted to receive cigars, a device for ejecting the cigar from the set of jaws at the discharging station of the turn-table and inserting it into a set of grippers on the turret, a conveyor adapted to carry the cigars to band-applying position, and an ejector for transferring cigars

from the turret to the conveyor. In the best constructions contemplated said means includes a pair of reciprocable slides movable into the space between the endless belts, and cam-actuated fingers on the slides for clamping the cigar to the slides, whereby it will be lodged in the set of jaws at the receiving station of the turn-table during the retreating stroke of the slides, and there is also provided means for simultaneously opening the sets of jaws at the receiving and discharging stations of the transfer or turn-table.

These various means and parts may be widely varied in construction for the particular mechanism selected to illustrate the invention is but one of many possible concrete embodiments of the same. The invention therefore, is not to be restricted to the specific construction shown and described.

Referring to the drawings, the cigars as in the combined wrapping and banding machine forming the subject matter of my Belgian Patent No. 395,520 and my prior application, S. N. 629,959 filed August 22, 1932, are placed in bulk into a magazine and by suitable means are delivered row by row onto the horizontally spaced feeding belts 10 (Fig. 2), running over intermittently driven pulleys 11 on shaft 12 and over idler pulleys, not shown. The cigars also pass under an endless top guide belt 13 running over an intermittently driven pulley 14 on shaft 15 and over idler pulleys, not shown. A gear 16 on shaft 12 drives a gear 17 on the shaft 15.

The shaft 18 constituting the main drive shaft of the cigar feed carries a series of cams 19, 20 and 21. Cam 19 engages a roller 22 carried by the bell crank lever 23 fulcrumed on the stud 24 mounted in the end frame 25 which is carried by the brackets 26 and 27 attached to the side frames 28 and 29 of the combined wrapping and banding machine. The end frame 25 is also secured to the magazine frame 30. The vertical arm of the bell crank lever 23 carries a link 31 which actuates an arm 32 mounted on a cross shaft 33 suitably supported in bearing brackets, not shown. A pair of spaced blocks 34, attached to shaft 33, carry the fingers 35 which are thereby periodically lowered into position to obstruct the advance of the cigars on belt 10. A pair of arms 36 also attached to shaft 33 carry pins 37 which encounter the lugs 38 on the hubs of the fingers 39, loose on shaft 15, when the arms 36 are depressed, thus lifting the fingers 39 from the cigars on belt 10. When the arms 36 are raised, springs 40 spanned from posts in the arms 36 to posts in the lugs 38 return the fingers 39 to

their original position in which they press the cigars immediately behind the leading cigar down on the belt 10 in front of guide belt 13 while the belts 10 and 13 are at rest and until the leading 5 cigar has been removed as hereinafter described, whereupon the movement of the belts 10 and 13 is resumed and the fingers 39 rise while the fingers 35 swing down into position to obstruct the next cigar.

10 The shaft 18 drives a sprocket 41 engaging the chain 42 and thus driving a sprocket 43 mounted on a shaft 44 supported in bearings 45 of the bracket 27. A crank 46 fastened to the end of shaft 44 is connected by a rod 47 to a lug 48 of 15 the driving member of a conventional ball clutch unit 49 on shaft 12 supported in the frames 30. The down stroke of rod 47 causes the ball clutch 49 to engage and turn shafts 12 and 15. Upon the completion of its down or driving stroke, the 20 arm 47 begins its upward stroke, thus disengaging the ball clutch 49 and permitting the shafts 12 and 15 to remain stationary. In this manner, an intermittent driving motion is imparted to the shafts 12 and 15.

25 A pinion 50 mounted on shaft 44 meshes with a gear 51 carried by a shaft 52 supported in bearings of the frames 30. The gear 51 in turn drives a gear train transmission, not shown, which drives the main shaft of a cigar magazine of the 30 type shown in my co-pending application S. N. 616,109 filed June 8, 1932.

The cam 20 (Fig. 3) mounted on shaft 18, actuates a roller 53 carried by a cam lever 54. The lever 54 is fulcrumed on a stud 55 supported 35 in a bearing 56 of the bracket 26 and is connected to the bell-crank lever 57 by means of an adjustable rod 58, lever 57 being pivotally mounted on a stud 58' carried by the block 59 of the vertical stationary rod 60. In the upper 40 end of lever 57 is set a pin 61 which carries a link 62, the other end of link 62 carrying a pin 63 on which is pivotally mounted a gripper finger 64. On the free end of finger 64 there is provided a roller 65 which engages the base of an 45 ejector plate 66. The pin 63 is held in a slide 67 which operates in tracks 68 and 69 carried by a block 70. The slide 67, by means of a tie bar 71 (Fig. 4) operates a like slide 72 which is mounted on the opposite side of the block in the 50 same manner as slide 67, wherefore like characters of reference will be used for corresponding parts, and the description of the same need not be repeated.

The block 59 on rod 60 is attached to the tie-bar 73. The horizontally extending arm 74 of lever 57 is equipped with a rod 75 which passes through an opening in bent arm 76, and about which is coiled a compression spring 77 so that the arm 76 will be moved up and down with the 60 arm 74 of lever 57. A block 78 attached to the arm 76 is pivoted on a stud 79 carried by the projecting end 80 of block 59, whereby the upward motion of arm 76 causes its vertical portion 81 (Fig. 1) to swing outward and expel the cigar 65 from the jaws then at the adjacent station of the transfer as will be hereinafter described.

The intermittently traveling conveyor chains 82 (Fig. 1) are driven in the same manner as disclosed in my Belgian patent and co-pending 70 application S. N. 629,959 referred to above. Chains 82 drive a pair of sprockets 83 on a shaft 84 which carries a gear 85 driving a pinion 86 on the turret shaft 87; and the latter carries a sprocket 88, a chain 89 running over sprocket 75 88 driving a sprocket 90 mounted on a shaft 91.

A bevel gear 92 on shaft 91 meshes with a bevel gear 93 rotating freely on the rod 60. The gear 93 supports the turn-table which consists of a plate 94 mounted on a slotted block 95 and provided at each side with a pair of integral depending fingers constituting jaws, and a like number of pairs of jaws 96 fitted into the slots of block 95 and pivotally mounted on pins 97 carried by the block to coat with the integral jaws of plate 94 to hold cigars inserted therebetween. Each of the jaws 96 is provided with a stud 98 carrying a spring 99 which is interposed between the finger and the base of gear 93, whereby each pair of jaws 96 holds the inserted cigar against the opposed jaws on plate 94.

The cam 21 actuates a roller 100 carried by a lever 101 fulcrumed on a stud 102 supported in a lug 103 (Fig. 3) of bracket 26, the slotted end of lever 101 engaging a pin 104 in a collar 105. Collar 105 and a collar 106 are clamped to a sleeve 107 which slides on the rod 60. The collar 106 is equipped with guide pins 108 which pass through slots in the slide block 70, the upper end of the pins 108 being fastened in the ejector plate 66. Ejector pins 109 on plate 66 are so arranged that they engage the inner ends of the grippers 96 (Fig. 4) at the cigar receiving and discharging stations.

When the leading cigar C in the row of cigars deposited on the belts 10 from the cigar magazine (Fig. 2) stops against the cam actuated fingers 35, which are then in their down position as indicated by the dotted lines, the clamp fingers 39 are in their raised position, and the conveyor belts 10 then momentarily stop and the fingers 35 are raised while the fingers 39 are lowered on the cigars immediately behind the leading cigar. The leading cigar is thus freed on the belts 10 while the cam-actuated slides 67 and 72 advance into the space between the belts 10 (Fig. 4) until the fingers 64 overlie the cigar. While the fingers 64 are advancing they are maintained in an elevated position by means of rollers 65 riding along the base of the ejector plate 66. Meanwhile the sleeve 107 rises, thus lifting the collar 106 with the plate 66 and permitting the tension springs 110 to press the fingers into engagement with the cigar to clamp it against the forward ends of the slides 67 and 72. During the ascent of plate 66 the ejector pins 109 are brought into engagement with the pairs of spring-tensioned jaws 96 then at the cigar receiving and discharging stations, thus lifting the same. The arm 81 of lever 76 in the meantime has moved towards the cigar C' then at the discharging station of the cigar transfer (Fig. 1) and finally pushes the same from the open jaws of the turn-table. A stop screw 111 engaging the lever 76 controls the extent of the movement of its arm 81.

In being pushed from the jaws of the turn-table the cigar encounters the fingers 112 which are carried by cam-actuated parallel levers (not shown) to move forward with the cigar C' and keep it from turning while being delivered to the pockets formed by the lifter frames 113 and the fingers 114. Reference may be had to my Belgian patent No. 395,520 or my prior application, S. N. 629,959, referred to above for a complete disclosure of the mechanism for actuating the fingers 112. The drive shaft 18 carries a bevel gear 115 which meshes with a gear, 116 mounted on shaft 117, thereby rotating cams (not shown) on shaft 117 which impart a reciprocating movement to the rods 118 relative to the lifters 113.

in which they are mounted, thereby causing the fingers 114 to come to rest on the cigar ejected from the jaws of the turn-table or transfer 84. The lifters 113 then move out to their dotted 5 position (Fig. 1) and then move vertically, thus inserting the cigar between one set of jaws of the turret mounted on shaft 87.

The turret consists of stationary grippers or jaws 120 and movable grippers or jaws 121, the 10 latter carrying pins 122 successively engaging cam-actuated knock-out arms not shown, which open the turret jaws. When the knock-out arms release the turret jaws 121, suitable springs press the jaws 121 against the inserted cigar to hold 15 the same against jaws 120. In the interim the rods 118 have been lifted to release the fingers 114 from the cigar, the lifters 113 then being moved back to their initial position in an arcuate path as indicated by the arrows, and are 20 then ready to receive the next cigar to be transferred. Further description of the mechanism for actuating the turret jaws 121 and the lifters 113 and fingers 114 is deemed unnecessary as reference may be had to my above mentioned 25 Belgian Patent No. 395,520 or my application S. N. 629,959, for a complete disclosure of the same.

Meanwhile the slides 67 and 72 have retreated and in so doing deposit the cigar C clamped 30 thereon by the fingers 64 (Fig. 3) in the jaws 94 and 96 then at the receiving station of the turn-table; at the completion of their retreating stroke the slides have moved back sufficiently to allow the turret 94 to turn. The arm 81 having 35 also been returned to its original position, the plate 66 descends, allowing the fingers 96 to clamp the cigar C.

The turn-table and the turret are then turned, the former carrying the cigar C to the discharge 40 position C' (Fig. 1), and the latter carries the cigar C' previously delivered thereto by the lifter 113, to the position C'' for delivering to the conveyor. At the latter position ejectors 123 and fingers 124 actuated as shown in my above 45 mentioned application S. N. 629,959, clamp the cigar C'' shortly before the knock-out arms engage the pins 122 of the movable turret jaws 121 and open all the turret jaws. The ejectors 123 and fingers 124 then advance the cigar towards 50 the adjacent pocket of the conveyor chains 82, the fingers 124 being mounted on reciprocable rods 125 and moving forward until they strike against the blocks 126 on guide rods 127, thereby moving the blocks until they rest against the 55 bracket 128. The blocks 126 in moving away from the fingers 130 and 131 which form the pockets of the conveyor, allow suitable springs to close the fingers upon the cigar C'' in the manner shown in my prior application S. N. 60 629,959. Thereupon the conveyor 82 advances step by step toward the banding unit B where a band is applied to the cigars.

The shaft 118 carries a plate cam 134 in one 65 face of which is provided a cam groove with which engages a cam roller carried by a bell-crank lever 150 loosely mounted on shaft 109a and connected by a link 152 to an arm 153 fastened on shaft 111a. The motion thus imparted to shaft 111a rocks the arms 157 attached to shaft 70 111a and the arms 157 loosely mounted on shaft 109a, the arms 157 being connected to the arms 156 by links 158. In this manner the fingers 112, which are a part of the links 158, are actuated.

Shaft 118 also carries plate cams 135 and 136 75 in one face of which are provided cam grooves

with which engage cam rollers carried by lugs 162 of the lifter frames 113, arms 164 mounted on shaft 109a being connected to the lugs 162. The opposite face of cams 135 and 136 is provided with cam grooves with which engage cam rollers 165 carried by arms 166 loosely mounted on shaft 109a. The extensions 167 of arms 166 are connected by links 168 to studs carried by lugs 169 of frames 113. On one face of the cams 135 and 136 are formed ledges 170 engaging rollers 171 mounted on blocks 172 attached to the spring-pressed rods 118 on the upper ends of which are fastened the fingers 114.

In the other face of the cam 134 is provided a cam groove with which engages a cam roller carried by a cam lever 202 fastened on shaft 110a, operating arms 203 having gear segments meshing with racks 205 of rods 125. The rods 125 carry the fingers 124 which slide on the plunger rods 127 carrying offset blocks 126. The rods 125 and 127 are mounted in brackets 128 fastened on shaft 84. The chains 82, which carry the sets of grippers 130 and 131, are intermittently driven by a Geneva gear (not shown) and drive sprockets 83 on shaft 84. The gear 85 on shaft 84 drives the pinion 86 on shaft 87 and thereby drives the turret which consists of the stationary members 120 and the movable members 121, the members 121 carrying pins 177 successively engaging knockout arms 178 clamped on shaft 106a. The cam surface on the periphery of the cam 133 operates arm 179 on shaft 109a carrying a link 180 attached to an arm 181 actuating the shaft 106a.

A cam lever 182 on shaft 109a provided with a cam roller engaging in a cam track of cam 133 actuates a rod 184 connected to a forked arm 186 clamped on shaft 107a journaled in pedestals 103a. Arms 187 clamped to shaft 107a are pivotally connected to the ejector 188 slidably mounted in grooves in the hubs of the stationary 35 turret members 176.

When the cigar C' ejected from the turn-table encounters the fingers 112 the latter move forward with the cigar and keep it from turning until it enters the pockets formed by the lifter frames 113 and the fingers 114. The turning of shaft 108 brings the low portions of cam ledges 170 beneath the cam rollers 171 on blocks 172, thus allowing the spring-tensioned rods 118 to descend and thereby causing the fingers 114 to come to rest on cigar C'. The revolving of cams 135 and 136 engaging the cam rollers carried by the lugs 162 of the lifter frames then raises the latter and lifts the cigar into the path of the turret. Then the cam-operated arm 178 descends and torsion springs (not shown) having one of their ends fixed in the movable turret members 176 and their other ends anchored to the shaft 87 return the jaws to rest against the cigar. In the interim the high portion of cam ledges 170 have come into engagement with the rollers 171, thus lifting the spring-tensioned rods 118 and releasing the fingers from the cigar. The continued rotation of cams 135 and 136, through arms 166 and 167, actuates the links 168 connected to lifter frames 113 which are thereby returned from their up position in a curved path, being then ready to receive the next cigar to be transferred.

What is claimed is:

1. The combination with endless belts adapted to horizontally feed a row of cigars sidewise in side by side contacting relation, of a turn-table revoluble about a vertical axis and provided with a plurality of sets of horizontal jaws at equal 70 75

intervals thereon, each set being adapted to grip a cigar inserted therebetween, means for horizontally transporting the leading cigar from said row and inserting it into the set of jaws then at the receiving station of said turn-table, mechanism for periodically turning said turn-table about its vertical axis through a fraction of one revolution to carry the gripped cigar to the discharging station of the turn-table and a device for ejecting the gripped cigar horizontally from the set of jaws at the discharging station of the turn-table.

2. The combination with spaced endless belts adapted to horizontally feed a row of cigars sideways, of a turn-table revoluble about a vertical axis and provided with a plurality of sets of horizontal jaws at equal intervals thereon, each set being adapted to grip a cigar inserted therebetween, means for horizontally transporting the leading cigar from said row and inserting it into the set of jaws then at the receiving station of said turn-table, mechanism for periodically turning said turn-table about its vertical axis through a fraction of one revolution to carry the gripped cigar to the discharging station of the turn-table and a device for ejecting the gripped cigar horizontally from the set of jaws at the discharging station of the turn-table, said means including a pair of reciprocable slides movable into the space between the endless belts, and spring-tensioned fingers on said slides for clamping said leading cigar in said row to said slides, whereby the cigar will be lodged in the set of jaws at the receiving station of the turn-table and thus released from said fingers during the retreating stroke of said slides.

3. The combination with spaced endless belts adapted to feed a row of cigars sideways, of a turn-table provided with a set of horizontal jaws adapted to receive a cigar therebetween, and means for horizontally transporting the leading cigar from said row and inserting it into said set of jaws, said means including a pair of reciprocable slides movable into the space between the endless belts, and spring-tensioned fingers on said slides for clamping the leading cigar in said row to said slides, whereby the cigar will be lodged in said set of jaws, and thus released from said fingers during the retreating stroke of said slides.

4. The combination with a turn-table revoluble about a vertical axis and provided with a plurality of sets of horizontal jaws, each set being adapted to grip a cigar inserted therebetween, means for inserting a cigar horizontally into the set of jaws at the receiving station of said turn-table, mechanism for periodically turning said turn-table about its vertical axis through a fraction of one revolution to carry the gripped cigar to the discharging station of the turn-table, means for gripping and ejecting the cigar horizontally from the set of jaws at the discharging station of the turn-table and carrying it away vertically while maintaining a grip thereon.

5. The combination with a turn-table revoluble about a vertical axis and provided with a set of jaws adapted to grip a cigar, and means for ejecting the cigar from said jaws, said means in-

cluding a cam-actuated lever adapted to eject the cigar from said jaws and movable lifters and fingers coacting to form a pocket in which the ejected cigar is received and carried away vertically.

6. The combination with a turn-table revoluble about a vertical axis and provided with a set of jaws adapted to grip a cigar, of means for inserting a cigar into said jaws, said means including a pair of reciprocable slides moving transversely of said jaws, and spring-pressed fingers mounted on said slides and adapted to clamp a cigar thereon, whereby a cigar clamped on said slides by said fingers will be lodged in the jaws and thus released from the fingers during the retreating stroke of the slides.

7. The combination with means for horizontally advancing a row of cigars sideways, of a conveyor extending transversely with respect to said row of cigars and including an endless series of grippers adapted to carry cigars sideways to band-applying position, and mechanism for periodically removing the leading cigar horizontally from said row and turning it in a horizontal plane to bring it into a position adjacent said conveyor and then delivering it to the grippers of said conveyor.

8. The combination with means for horizontally advancing a row of cigars sideways, of a conveyor extending transversely with respect to said row of cigars and adapted to carry cigars sideways to band-applying position, and mechanism for periodically removing the leading cigar horizontally from said row and turning it in a horizontal plane to bring it into a position adjacent said conveyor and then delivering it to the conveyor, said means including a set of intermittently driven endless belts, and said mechanism operating to grip and remove the leading cigar from said row while the same is at rest and continue gripping the cigar until it is delivered to said conveyor.

9. The combination with means for advancing a row of cigars sideways in side by side contacting relation, of a conveyor extending transversely with respect to said row of cigars and adapted to carry cigars sideways to band-applying position, and mechanism for periodically removing the leading cigar from said row and turning it in a horizontal plane to bring it into a position adjacent said conveyor and then delivering it to the conveyor, said mechanism operating to grip the cigar while removing it from said row and continue gripping it until it is delivered to said conveyor.

10. The combination with means for advancing a row of cigars sideways, of a conveyor disposed at right angles to said row of cigars and including an endless member and sets of grippers carried by said member and adapted to carry cigars sideways to band-applying position, and mechanism for periodically removing the leading cigar from said row and turning it horizontally through an arc of 90 degrees to bring it into a position aligned with said conveyor and then delivering it to a set of grippers of said conveyor.

JOSEPH A. NEUMAIR.
